[57] CLAIM

The ornamental design for a jumping frog, as shown.

DESCRIPTION

FIG. 1 is a front and top perspective view of a jumping frog embodying my new design;

FIG. 2 is a front view of the frog;

FIG. 3 is a side view of the frog;

FIG. 4 is a top plan view of the frog;

FIG. 5 is a side view of the frog opposite that shown in FIG. 1;

FIG. 6 is a rear view of the frog;

FIG. 7 is a bottom plan view of the frog; and,

FIG. 8 is a front and top perspective view of a modification thereof.
